(57) **ABSTRACT**

A sheet conveying device can selectively execute a first conveyance process of conveying sheets on a first tray and discharging the sheets onto a second tray, a second conveyance process of conveying the sheets on the first tray and discharging the sheets onto a third tray, or a third conveyance process of conveying the sheets on the third tray and discharging the sheets onto the second tray. A control device records conveyance history information indicating by which conveyance processes each of the sheets on the first tray has been conveyed in a storage device. Furthermore, the control device causes the sheet conveying device to sequentially select the first conveyance process or the third conveyance process for each of the sheets based on the conveyance history information and execute the selected process.

**IMAGE READING APPARATUS CAPABLE
OF SELECTING DOCUMENT SHEET
CONVEYANCE PROCESS**

INCORPORATION BY REFERENCE

This application is based upon and claims the benefit of priority from the corresponding Japanese Patent Application No. 2021-044025 filed on Mar. 17, 2021, the entire contents of which are incorporated herein by reference.

BACKGROUND

The present disclosure relates to a sheet processing control method and a sheet processing apparatus capable of sorting sheets discharged separately to two trays in the original order.

An image reading apparatus often includes a document sheet conveying device and an image reading portion that reads images from document sheets conveyed by the document sheet conveying device. The document sheet conveying device conveys the document sheets stacked on a supply tray one by one along a conveyance path and discharges the document sheets from the conveyance path to a discharge tray.

The document sheets are an example of sheets, and the image reading apparatus is an example of a sheet processing apparatus. The sheet processing apparatus conveys the sheets and executes predetermined sheet processing on the conveyed sheets. In the image reading apparatus, the sheet processing is a process of reading images from the sheets.

In addition, the image reading apparatus is known to detect images of identification codes from the images read from the document sheets conveyed by the document sheet conveying device and to determine whether there are any missing pages in the document sheets based on the result of detection of the identification codes.

SUMMARY

A sheet processing control method according to an aspect of the present disclosure is a method of controlling a sheet processing apparatus. The sheet processing apparatus includes a first tray, a second tray, and a third tray on which sheets can be stacked; a sheet conveying device; and a sheet processing portion. The sheet conveying device is capable of selectively executing a first conveyance process, a second conveyance process, and a third conveyance process. The first conveyance process is a process of conveying the sheets on the first tray one by one along a first conveyance path and then discharging the sheets onto the second tray. The second conveyance process is a process of conveying the sheets on the first tray one by one along a second conveyance path and then discharging the sheets onto the third tray. The third conveyance process is a process of conveying the sheets on the third tray one by one along a third conveyance path and then discharging the sheets onto the second tray. The sheet processing portion is configured to execute a process set in advance on the sheets conveyed by the first conveyance process or the second conveyance process. The sheet processing control method includes executing a first control when a first start event set in advance occurs, the first control causing the sheet conveying device to selectively execute the first conveyance process or the second conveyance process. The sheet processing control method further includes recording conveyance history information in a storage device, the conveyance history information indicat-

2

ing by which of the first conveyance process and the second conveyance process each of the sheets on the first tray has been conveyed in the first control. The sheet processing control method further includes executing a second control when a second start event set in advance occurs, the second control causing the sheet conveying device to sequentially select the first conveyance process or the third conveyance process for each of the sheets based on the conveyance history information and execute the selected process.

10 A sheet processing apparatus according to another aspect of the present disclosure includes the first tray, the second tray, and the third tray; the sheet conveying device; the sheet processing portion; and a control portion capable of executing a process of the sheet processing control method.

15 This Summary is provided to introduce a selection of concepts in a simplified form that are further described below in the Detailed Description with reference where appropriate to the accompanying drawings. This Summary is not intended to identify key features or essential features of the claimed subject matter, nor is it intended to be used to limit the scope of the claimed subject matter. Furthermore, the claimed subject matter is not limited to implementations that solve any or all disadvantages noted in any part of this disclosure.

25 BRIEF DESCRIPTION OF THE DRAWINGS

FIG. 1 is a configuration diagram of an image reading apparatus according to an embodiment.

30 FIG. 2 is a configuration diagram of a main part of the image reading apparatus according to the embodiment.

FIG. 3 is a block diagram showing a configuration of a control device in the image reading apparatus according to the embodiment.

35 FIG. 4 is a flowchart showing an example of a procedure of a reading control in a sorting mode in the image reading apparatus according to the embodiment.

FIG. 5 is a flowchart showing an example of a procedure of a document sheet sorting control in the image reading 40 apparatus according to the embodiment.

DETAILED DESCRIPTION

The following describes an embodiment of the present disclosure with reference to the accompanying drawings. It should be noted that the following embodiment is an example of a specific embodiment of the present disclosure and should not limit the technical scope of the present disclosure.

50 [Configuration of Image Reading Apparatus 1]

An image reading apparatus 1 is an example of a sheet processing apparatus configured to convey sheets and execute sheet processing on the conveyed sheets. The sheets to be conveyed by the image reading apparatus 1 are document sheets 9 (see FIG. 1) having surfaces on which images are formed.

As shown in FIG. 1, the image reading apparatus 1 includes a body portion 11 and a cover portion 12 that covers the upper surface of the body portion 11. The body portion 11 is a housing that houses various types of devices. The cover portion 12 is supported to be displaceable between a closed position at which the cover portion 12 covers the upper surface of the body portion 11 and an open position at which the cover portion 12 opens the upper surface of the body portion 11. The cover portion 12 is displaceably supported by a hinge (not shown) provided for the body portion 11.

The image reading apparatus 1 further includes a contact glass 64 and a platen glass 65 disposed on the upper surface of the body portion 11. The contact glass 64 and the platen glass 65 are transparent plate-like members.

The image reading apparatus 1 further includes a document sheet conveying device 2, an image reading portion 6, a moving mechanism 7, a control device 8, an operation device 801, and a display device 802. The document sheet conveying device 2 is integrated into the cover portion 12.

The document sheet conveying device 2 includes a supply tray 3a, a discharge tray 3b, a conveyance path 40, a conveying mechanism 4, a supplied document sheet sensor 5a, and a conveyed document sheet sensor 5b. The conveyance path 40 forms a path along which the document sheets 9 are conveyed.

The document sheets 9 can be stacked on the supply tray 3a and the discharge tray 3b. The supply tray 3a is an example of a first tray, and the discharge tray 3b is an example of a second tray. In the present embodiment, the discharge tray 3b is disposed below the supply tray 3a.

The supplied document sheet sensor 5a detects the document sheets 9 placed on the supply tray 3a. For example, the supplied document sheet sensor 5a includes a first displaceable member and a first detection sensor (both not shown).

The first displaceable member is displaced to a lower position below an upper position serving as an initial position upon receiving the load of the document sheets 9 on the supply tray 3a. The first detection sensor detects the first displaceable member displaced to the lower position.

The conveyed document sheet sensor 5b detects the document sheets 9 fed from the supply tray 3a to the conveyance path 40. For example, the conveyed document sheet sensor 5b includes a second displaceable member and a second detection sensor (both not shown).

The second displaceable member is displaced from a reference position to a retracted position by coming into contact with the document sheets 9 fed from the supply tray 3a to the conveyance path 40. The second detection sensor detects the second displaceable member displaced to the retracted position.

The conveying mechanism 4 feeds the document sheets 9 on the supply tray 3a one by one to the conveyance path 40, conveys the document sheets 9 along the conveyance path 40, and then discharges the document sheets 9 onto the discharge tray 3b. The conveying mechanism 4 is an example of a sheet conveying device.

In the description below, a horizontal direction along which the document sheets 9 are fed from the supply tray 3a is referred to as "first direction D1", and a direction opposite the first direction D1 is referred to as "second direction D2". In addition, a horizontal direction orthogonal to the first direction D1 and the second direction D2 is referred to as "third direction D3".

As shown in FIG. 2, the conveyance path 40 includes a first incoming path 40a, a return path 40b, and a first outgoing path 40c. The first incoming path 40a extends from a first entrance 401 corresponding to the supply tray 3a in the first direction D1. The conveyed document sheet sensor 5b detects the document sheets 9 fed to the first incoming path 40a.

The return path 40b is a curved path connected to the first incoming path 40a and turning back in the second direction D2 opposite the first direction D1. The first outgoing path 40c is connected to the return path 40b and extends in the second direction D2 to lead to a first exit 403 corresponding

to the discharge tray 3b. The first outgoing path 40c leads to the first exit 403 via a position along the upper surface of the contact glass 64.

The conveying mechanism 4 includes a first feed mechanism 41 corresponding to the supply tray 3a and pairs of conveying rollers 43 disposed along the conveyance path 40.

The first feed mechanism 41 feeds the document sheets 9 on the supply tray 3a one by one to the first incoming path 40a. In the present embodiment, the first feed mechanism 41 feeds the topmost sheet in the document sheets 9 on the supply tray 3a to the first incoming path 40a.

The pairs of conveying rollers 43 are rotationally driven by motors (not shown) to convey the document sheets 9 along the conveyance path 40.

15 The image reading portion 6 executes an image reading process of reading images formed on the document sheets 9 and outputting image data representing the read images. In the present embodiment, the image reading portion 6 includes a first image reading portion 61, a second image reading portion 62, and an AFE (Analog Front End) 60.

In the description below, the upper surfaces of the document sheets 9 placed on the supply tray 3a are referred to as "first sides", and the lower surfaces of the document sheets 9 placed on the supply tray 3a are referred to as "second sides".

20 The first image reading portion 61 reads images on the first sides of the document sheets 9 passing through the first outgoing path 40c while being at a position corresponding to the contact glass 64. The second image reading portion 62 reads images on the second sides of the document sheets 9 passing through the first incoming path 40a.

In the present embodiment, the first image reading portion 61 and the second image reading portion 62 each include a light-emitting portion 6a, a lens 6b, and an image sensor 6c (see FIG. 1). The light-emitting portions 6a, the lenses 6b, and the image sensors 6c extend in the third direction D3.

25 The light-emitting portions 6a emit light beams onto document sheets 9. The lenses 6b guide the light beams reflected from the document sheets 9 to the respective image sensors 6c. The image sensors 6c are line sensors that determine the intensity of the light beams reflected from the document sheets 9 and that output detection signals as image signals.

The AFE 60 converts the image signals into digital image data. In the example shown in FIG. 1, the first image reading portion 61 and the second image reading portion 62 are CISs (Contact Image Sensors) each including the light-emitting portion 6a, the lens 6b, and the image sensor 6c of the CMOS (Complementary Metal Oxide Semiconductor) type integrated together.

30 The moving mechanism 7 moves the first image reading portion 61 in a range from the position facing the contact glass 64 to a position facing the platen glass 65.

In a case where the document sheets 9 are conveyed by 35 the conveying mechanism 4, the moving mechanism 7 keeps the first image reading portion 61 at the position facing the contact glass 64.

In a case where the document sheets 9 are placed on the platen glass 65, the moving mechanism 7 moves the first image reading portion 61 along the platen glass 65. Thus, the image sensor 6c of the first image reading portion 61 reads the images on the document sheets 9 while the light-emitting portion 6a of the first image reading portion 61 scans the light beam over the document sheets 9 on the platen glass 65.

40 That is, when the conveying mechanism 4 operates, the image reading portion 6 executes the image reading process on the document sheets 9 conveyed along the conveyance

path 40. In contrast, when the conveying mechanism 4 does not operate, the image reading portion 6 executes the image reading process on the document sheets 9 placed on the platen glass 65.

It is noted that the image sensor 6c of the first image reading portion 61 may be a CCD (Charge Coupled Device) sensor. In this case, the moving mechanism 7 moves the light-emitting portion 6a and the lens 6b while the image sensor 6c of the CCD type is fixed at a predetermined position.

The operation device 801 is configured to receive operations from users and includes, for example, operation buttons and a touch panel. The display device 802 is configured to display information and includes, for example, a panel display device such as a liquid crystal display unit.

The control device 8 executes various types of data processing and controls the image reading apparatus 1. As shown in FIG. 3, the control device 8 includes a CPU (Central Processing Unit) 81, a RAM (Random Access Memory) 82, a secondary storage device 83, and peripherals such as a signal interface 84.

The secondary storage device 83 is a computer-readable nonvolatile storage device. The secondary storage device 83 can store and update computer programs and various types of data. For example, either a flash memory or a hard disk drive, or both, may be adopted as the secondary storage device 83.

The signal interface 84 converts signals output by various types of sensors into digital data and transmits the converted digital data to the CPU 81. Furthermore, the signal interface 84 converts control commands output by the CPU 81 into control signals and transmits the control signals to devices to be controlled.

The CPU 81 is a processor that executes the computer programs to execute various types of data processing and control. The RAM 82 is a computer-readable volatile storage device. The RAM 82 primarily stores the computer programs executed by the CPU 81 and data that is output or consulted by the CPU 81 during execution of various types of processing.

The CPU 81 includes a plurality of processing modules that are implemented when the computer programs are executed. The plurality of processing modules include a main control portion 8a, a conveyance control portion 8b, and a reading control portion 8c.

The main control portion 8a executes control that causes various types of processing to be started in response to operations on the operation device 801 and executes control of the display device 802.

The conveyance control portion 8b controls the conveying mechanism 4 to control the conveyance of the document sheets 9. The reading control portion 8c controls the image reading portion 6 to cause the image reading portion 6 to execute the image reading process.

The conveying mechanism 4 conveys the document sheets 9 along the return path 40b on the conveyance path 40. The return path 40b is a curved conveyance path along which the conveyance direction of the document sheets 9 is reversed.

For example, when a thick document sheet 9 is conveyed along the return path 40b, the document sheet 9 may be damaged. The thick document sheet 9 is an example of a sheet unsuitable for the conveyance along the return path 40b.

Accordingly, the sheet processing apparatus such as the image reading apparatus 1 capable of selectively executing a reverse conveyance process or a straight conveyance process can reduce damage to the sheet. In the present

embodiment, the document sheet conveying device 2 further includes an auxiliary tray 3c (see FIGS. 1 and 2) on which the document sheets 9 can be stacked.

The reverse conveyance process is a process of conveying the document sheets 9 on the supply tray 3a to discharge the document sheets 9 onto the discharge tray 3b via the return path 40b. The straight conveyance process is a process of conveying the document sheets 9 on the supply tray 3a along a conveyance path branching off upstream of the return path 10 40b to discharge the document sheets 9 not to the discharge tray 3b but to the auxiliary tray 3c.

However, in a case where the document sheets 9 stacked on the supply tray 3a are discharged separately to the discharge tray 3b and the auxiliary tray 3c, sorting the 15 document sheets 9 stacked on the two different trays in the original order is time consuming.

The conveying mechanism 4 of the image reading apparatus 1 has a configuration capable of selectively executing 20 the reverse conveyance process or the straight conveyance process. Furthermore, the image reading apparatus 1 has a function of sorting the document sheets 9 discharged separately to the discharge tray 3b and the auxiliary tray 3c in the original order.

25 As shown in FIGS. 1 and 2, the auxiliary tray 3c are disposed at a position away from the supply tray 3a and the discharge tray 3b in the first direction D1. The auxiliary tray 3c is an example of a third tray. For example, the auxiliary tray 3c may be collapsible along the outer edge of the cover portion 12.

30 The conveyance path 40 further includes a second outgoing path 40d and a second incoming path 40e. The second outgoing path 40d is connected to the first incoming path 40a and extends in the first direction D1 to lead to a second 35 exit 404 corresponding to the auxiliary tray 3c. That is, the conveyance path 40 branches off from the first incoming path 40a to the return path 40b and the second outgoing path 40d.

The second incoming path 40e extends from a second 40 entrance 402 corresponding to the auxiliary tray 3c in the second direction D2 to be connected to the first outgoing path 40c. That is, the return path 40b and the second incoming path 40e join the first outgoing path 40c.

The conveying mechanism 4 further includes a path 45 switching mechanism 44 and a second feed mechanism 42. In addition, the document sheet conveying device 2 further includes a conveyed document sheet sensor 5c (see FIG. 2) corresponding to the second feed mechanism 42. In addition, the image reading apparatus 1 further includes a third image reading portion 63 partly constituting the image reading portion 6.

50 The path switching mechanism 44 selectively guides the document sheets 9 conveyed along the first incoming path 40a to either the return path 40b or the second outgoing path 40d.

The second feed mechanism 42 feeds the document sheets 9 on the auxiliary tray 3c one by one to the second incoming path 40e. In the present embodiment, the second feed mechanism 42 feeds the topmost sheet in the document 55 sheets 9 on the auxiliary tray 3c to the second incoming path 40e.

The conveyed document sheet sensor 5c detects the document sheets 9 fed from the auxiliary tray 3c to the second incoming path 40e. The conveyed document sheet sensor 5c has a configuration identical to that of the conveyed document sheet sensor 5b corresponding to the first feed mechanism 41.

In the description below, part of the conveyance path **40** from the first incoming path **40a** to the first outgoing path **40c** via the return path **40b** is referred to as "first conveyance path **40a-40c**". Moreover, part of the conveyance path **40** from the first incoming path **40a** to the second outgoing path **40d** is referred to as "second conveyance path **40a-40d**". In addition, part of the conveyance path **40** from the second incoming path **40e** to the first outgoing path **40c** is referred to as "third conveyance path **40e-40c**".

The conveying mechanism **4** can perform a first operation of guiding the document sheets **9** to the return path **40b** using the path switching mechanism **44** while operating the first feed mechanism **41** and the pairs of conveying rollers **43**.

Moreover, the conveying mechanism **4** can perform a second operation of guiding the document sheets **9** to the second outgoing path **40d** using the path switching mechanism **44** while operating the first feed mechanism **41** and the pairs of conveying rollers **43**.

Furthermore, the conveying mechanism **4** can perform a third operation of operating the second feed mechanism **42** and the pairs of conveying rollers **43**.

The conveying mechanism **4** performs the first operation to execute a first conveyance process of conveying the document sheets **9** on the supply tray **3a** one by one along the first conveyance path **40a-40c** and then discharging the document sheets **9** onto the discharge tray **3b**. The first conveyance process corresponds to the reverse conveyance process.

In addition, the conveying mechanism **4** performs the second operation to execute a second conveyance process of conveying the document sheets **9** on the supply tray **3a** one by one along the second conveyance path **40a-40d** and then discharging the document sheets **9** onto the auxiliary tray **3c**. The second conveyance process corresponds to the straight conveyance process.

The third image reading portion **63** reads images on the first sides of the document sheets **9** passing through the second outgoing path **40d**. The third image reading portion **63** has a configuration identical to that of the second image reading portion **62**.

In addition, the conveying mechanism **4** performs the third operation to execute a third conveyance process of conveying the document sheets **9** on the auxiliary tray **3c** one by one along the third conveyance path **40e-40c** and then discharging the document sheets **9** onto the discharge tray **3b**.

The conveying mechanism **4** can selectively execute the first conveyance process, the second conveyance process, or the third conveyance process according to the control by the conveyance control portion **8b**.

The image reading apparatus **1** further includes a thickness sensor **5d** (see FIG. 2). The thickness sensor **5d** determines the thicknesses of the document sheets **9** conveyed along the first incoming path **40a**. For example, the thickness sensor **5d** determines the capacitances of the document sheets **9**. The document sheets **9** with higher capacitances have greater thicknesses.

The main control portion **8a** starts a reading control in a sorting mode (see FIG. 4) when a predetermined first start event occurs. For example, the first start event is an event where a predetermined start operation performed on the operation device **801** is detected while the document sheets **9** on the supply tray **3a** are detected by the supplied document sheet sensor **5a**.

The reading control in the sorting mode includes causing the conveying mechanism **4** to convey the document sheets **9** and causing the image reading portion **6** to execute the image reading process.

5 [Reading Control in Sorting Mode]

The following describes an example of a procedure of the reading control in the sorting mode with reference to a flowchart shown in FIG. 4. The reading control in the sorting mode is an embodiment of a sheet processing control method.

10 In the following description, **S101**, **S102**, . . . are identification signs representing a plurality of steps in the reading control in the sorting mode. In the reading control in the sorting mode, a process in step **S101** is started first.

15 <Step S101>

In step **S101**, the conveyance control portion **8b** causes the first feed mechanism **41** to feed a document sheet **9** and then moves the process to step **S102**. In addition, the reading control portion **8c** executes a process in step **S105** while the conveyance control portion **8b** executes processes in steps **S102** to **S104**.

20 <Step S102>

In step **S102**, the conveyance control portion **8b** determines whether the thickness of the document sheet **9** is less than or equal to a predetermined reference value or exceeds the reference value based on the value determined by the thickness sensor **5d**.

25 Upon determining that the thickness of the document sheet **9** is less than or equal to the reference value, the conveyance control portion **8b** moves the process to step **S103**. Otherwise, the conveyance control portion **8b** moves the process to step **S104**.

30 <Step S103>

In step **S103**, the conveyance control portion **8b** causes the conveying mechanism **4** to execute the first conveyance process. Specifically, the conveyance control portion **8b** controls the path switching mechanism **44** such that the document sheet **9** is guided to the return path **40b**. Subsequently, the conveyance control portion **8b** moves the process to step **S106**.

35 <Step S104>

In step **S104**, the conveyance control portion **8b** causes the conveying mechanism **4** to execute the second conveyance process. Specifically, the conveyance control portion **8b** controls the path switching mechanism **44** such that the document sheet **9** is guided to the second outgoing path **40d**. Subsequently, the conveyance control portion **8b** moves the process to step **S106**.

40 As described above, the conveyance control portion **8b** executes the control in steps **S102** to **S104** when the first start event occurs. The control in steps **S102** to **S104** is an example of a first control that causes the conveying mechanism **4** to selectively execute the first conveyance process or the second conveyance process.

45 In addition, in the first control, the conveyance control portion **8b** selects which of the first conveyance process and the second conveyance process is to be executed by the conveying mechanism **4** (step **S102**) based on the result of determination by the thickness sensor **5d**.

50 <Step S105>

In step **S105**, the reading control portion **8c** causes the image reading portion **6** to execute the image reading process. Subsequently, the reading control portion **8c** moves the process to step **S106**.

55 In a case where the first conveyance process is executed while a two-sided reading mode is selected as an operation mode in advance, the reading control portion **8c** causes the

second image reading portion 62 and the first image reading portion 61 to sequentially execute the image reading process.

In a case where the second conveyance process is executed while the two-sided reading mode is selected as the operation mode in advance, the reading control portion 8c causes the second image reading portion 62 and the third image reading portion 63 to sequentially execute the image reading process.

In a case where the first conveyance process is executed while a one-sided reading mode is selected as the operation mode in advance, the reading control portion 8c causes the first image reading portion 61 to execute the image reading process.

In a case where the second conveyance process is executed while the one-sided reading mode is selected as the operation mode in advance, the reading control portion 8c causes the third image reading portion 63 to execute the image reading process.

The reading control portion 8c controls the timing at which the image reading portion 6 is to be operated based on the timing at which the conveyed document sheet sensor 5b changes its state from "not detecting the document sheet 9" to "detecting the document sheet 9". Furthermore, the reading control portion 8c controls the timing at which the image reading portion 6 is to be stopped based on the timing at which the conveyed document sheet sensor 5b changes its state from "detecting the document sheet 9" to "not detecting the document sheet 9".

The image reading portion 6 is an example of a sheet processing portion that executes predetermined processes on the sheet conveyed by the first conveyance process or the second conveyance process.

<Step S106>

In step S106, the conveyance control portion 8b records conveyance history information in the secondary storage device 83 and moves the process to step S107.

The conveyance history information indicates by which of the first conveyance process and the second conveyance process each document sheet 9 on the supply tray 3a has been conveyed in the control in steps S102 to S104.

For example, the conveyance history information includes total count information and document sheet number information. The total count information indicates the total number of document sheets 9 fed by the first feed mechanism 41 after the occurrence of the first start event. The document sheet number information indicates the ordinal positions of the document sheets 9 subjected to the first conveyance process.

The conveyance control portion 8b counts the number of document sheets 9 fed by the first feed mechanism 41 by counting the number of changes in the state of the conveyed document sheet sensor 5b occurring when the conveyed document sheet sensor 5b detects the document sheets 9.

<Step S107>

In step S107, the conveyance control portion 8b determines whether there are any document sheets 9 on the supply tray 3a based on the detection state of the supplied document sheet sensor 5a. Upon determining that there is one or more document sheets 9 on the supply tray 3a, the conveyance control portion 8b moves the process to step S101. Otherwise, the conveyance control portion 8b moves the process to step S108.

<Step S108>

In step S108, the conveyance control portion 8b determines whether the document sheets 9 need to be sorted based on the conveyance history information.

Specifically, the conveyance control portion 8b determines that the document sheets 9 do not need to be sorted in a case where the conveyance history information indicates that all the document sheets 9 are conveyed by the first conveyance process. Otherwise, the conveyance control portion 8b determines that the document sheets 9 need to be sorted.

Upon determining that the document sheets 9 do not need to be sorted, the conveyance control portion 8b ends the reading control in the sorting mode. Otherwise, the conveyance control portion 8b moves the process to step S109.

<Step S109>

In step S109, the main control portion 8a displays guide information in the display device 802. The guide information indicates operations to be performed by users before document sheet sorting control (described later) starts.

The guide information includes information that prompts the users to perform an operation for starting the document sheet sorting control. In the present embodiment, the main control portion 8a changes the information included in the guide information according to the content of the conveyance history information.

Specifically, in a case where the conveyance history information indicates that a part of the document sheets 9 is conveyed by the first conveyance process in the control in steps S102 to S104, the main control portion 8a includes document sheet moving guide information in the guide information. The document sheet moving guide information provides guidance on how one or more document sheets 9 on the discharge tray 3b are moved onto the supply tray 3a.

The leading edges of the document sheets 9 on the discharge tray 3b face a direction opposite the direction the leading edges of the document sheets 9 on the supply tray 3a face, and the first sides of the document sheets 9 on the discharge tray 3b face a direction opposite the direction the first sides of the document sheets 9 on the supply tray 3a face. In addition, compared with the document sheets 9 on the supply tray 3a, the document sheets 9 stacked on the discharge tray 3b are stacked in reverse order from bottom to top.

The leading edges of the document sheets 9 on the auxiliary tray 3c face the same direction as the leading edges of the document sheets 9 on the supply tray 3a, and the first sides of the document sheets 9 on the auxiliary tray 3c face the same direction as the first sides of the document sheets 9 on the supply tray 3a. In addition, compared with the document sheets 9 on the supply tray 3a, the document sheets 9 stacked on the auxiliary tray 3c are stacked in reverse order from bottom to top.

In the above-described case, the document sheet moving guide information provides guidance on moving the document sheets 9 on the discharge tray 3b onto the supply tray 3a without changing the direction the leading edges face and the direction the first sides face.

In addition, the main control portion 8a may include information that provides guidance on not changing the directions the document sheets 9 on the auxiliary tray 3c face in the guide information. Furthermore, the main control portion 8a may include information that prompts the users to align the edges of the document sheets 9 on the auxiliary tray 3c facing the second direction D2 to the position of the second feed mechanism 42 in the guide information.

The process in step S109 is executed at a point in time after the control in steps S102 to S104 has started and before the document sheet sorting control (described later) starts.

11

After displaying the guide information in the display device 802, the main control portion 8a moves the process to step S110.

<Step S110>

In step S110, the conveyance control portion 8b executes the document sheet sorting control when a predetermined second start event occurs. In the present embodiment, the second start event is an event where an operation for starting the document sheet sorting control is performed on the operation device 801.

After executing the document sheet sorting control, the conveyance control portion 8b ends the reading control in the sorting mode.

[Document Sheet Sorting Control]

The following describes an example of a procedure of the document sheet sorting control with reference to a flowchart shown in FIG. 5.

In the following description, S201, S202, . . . are identification signs representing a plurality of steps in the document sheet sorting control. In the document sheet sorting control, a process in step S201 is started first.

<Step S201>

In step S201, the conveyance control portion 8b acquires the conveyance history information from the secondary storage device 83. Subsequently, the conveyance control portion 8b moves the process to step S202.

<Step S202>

In step S202, the conveyance control portion 8b selects either the supply tray 3a or the auxiliary tray 3c as a source tray according to a predetermined selection rule based on the conveyance history information. The source tray is a tray from which the document sheets 9 are fed in step S203 or S204.

The selection rule is established such that the document sheets 9 stacked on the supply tray 3a and the auxiliary tray 3c are stacked on the discharge tray 3b in the original page order when the document sheets 9 are conveyed to the discharge tray 3b. The original page order corresponds to the page order of the document sheets 9 on the supply tray 3a when the reading control in the sorting mode starts.

The conveyance control portion 8b moves the process to step S203 upon selecting the supply tray 3a as the source tray, whereas the conveyance control portion 8b moves the process to step S204 upon selecting the auxiliary tray 3c as the source tray.

<Step S203>

In step S203, the conveyance control portion 8b causes the conveying mechanism 4 to execute the first conveyance process and then moves the process to step S205. The control in step S203 causes the topmost sheet in the document sheets 9 on the supply tray 3a to be conveyed to the discharge tray 3b.

<Step S204>

In step S204, the conveyance control portion 8b causes the conveying mechanism 4 to execute the third conveyance process and then moves the process to step S205. The control in step S204 causes the topmost sheet in the document sheets 9 on the auxiliary tray 3c to be conveyed to the discharge tray 3b.

<Step S205>

In step S205, the conveyance control portion 8b determines whether an end condition that indicates all the document sheets 9 on the supply tray 3a and the auxiliary tray 3c have been conveyed is achieved.

For example, the conveyance control portion 8b determines that the end condition is achieved when the number of times the first conveyance process in step S203 and the third

12

conveyance process in step S204 are executed reaches the total number in the conveyance history information.

Upon determining that the end condition is achieved, the conveyance control portion 8b ends the sorting control. 5 Otherwise, the conveyance control portion 8b moves the process to step S202.

The control in steps S202 to S205 by the conveyance control portion 8b is an example of a second control that causes the conveying mechanism 4 to sequentially select the 10 first conveyance process or the third conveyance process for each of the document sheets 9 based on the conveyance history information and execute the selected process when the second start event occurs.

The adoption of the image reading apparatus 1 allows the 15 document sheet conveying device 2 to sort the document sheets 9 discharged separately to two trays in the original order with a simple operation.

First Application Example

The following describes a sheet processing apparatus according to a first application example of the image reading apparatus 1. The sheet processing apparatus according to the present application example may have a configuration in which the image reading portion 6 in the image reading apparatus 1 is replaced with another sheet processing portion.

For example, instead of the image reading portion 6, the sheet processing portion may be a punching mechanism that 30 punches holes in the sheets conveyed by the conveying mechanism 4. The sheet processing apparatus according to the present application example produces effects similar to those produced by the image reading apparatus 1.

Second Application Example

Next, the following describes a sheet processing apparatus according to a second application example of the image reading apparatus 1. In the present application example, the main control portion 8a sets specific information indicating the ordinal positions of the document sheets 9 that are to be subjected to the second conveyance process based on specific operations on the operation device 801.

Furthermore, in step S102 in FIG. 4, the conveyance control portion 8b according to the present application example selects which of the first conveyance process and the second conveyance process is to be executed by the conveying mechanism 4 based on the specific information.

The sheet processing apparatus according to the present application example produces effects similar to those produced by the image reading apparatus 1.

It is to be understood that the embodiments herein are illustrative and not restrictive, since the scope of the disclosure is defined by the appended claims rather than by the description preceding them, and all changes that fall within metes and bounds of the claims, or equivalence of such metes and bounds thereof are therefore intended to be embraced by the claims.

The invention claimed is:

1. An image reading apparatus comprising:
a first tray on which document sheets can be stacked;
a second tray which is disposed below the first tray and on
which the document sheets can be stacked;
a third tray which is disposed at a position away from the
first tray and the second tray in a horizontal first
direction and on which the document sheets can be
stacked;

13

a first conveyance path including: a first incoming path extending from a first entrance corresponding to the first tray in the first direction; a return path connected to the first incoming path and turning back in a second direction opposite the first direction; and a first outgoing path connected to the return path and extending in the second direction to lead to a first exit corresponding to the second tray;

a second conveyance path including: the first incoming path; and a second outgoing path connected to the first incoming path and extending in the first direction to lead to a second exit corresponding to the third tray;

a third conveyance path including: a second incoming path extending from a second entrance corresponding to the third tray in the second direction to be connected to the first outgoing path; and the first outgoing path;

a document sheet conveying device capable of selectively executing a first conveyance process of conveying the document sheets on the first tray one by one along the first conveyance path and then discharging the document sheets onto the second tray, a second conveyance process of conveying the document sheets on the first tray one by one along the second conveyance path and then discharging the document sheets onto the third tray, or a third conveyance process of conveying the document sheets on the third tray one by one along the third conveyance path and then discharging the document sheets onto the second tray;

an image reading portion configured to execute an image reading process for reading images from the document sheets conveyed by the first conveyance process or the second conveyance process; and

a control portion configured to control the document sheet conveying device, wherein

the control portion executes a first control when a first start event set in advance occurs, the first control

5

10

15

20

25

30

14

causing the document sheet conveying device to selectively execute the first conveyance process or the second conveyance process;

the control portion further records conveyance history information in a storage device, the conveyance history information indicating by which of the first conveyance process and the second conveyance process each of the document sheets on the first tray has been conveyed in the first control; and

the control portion further executes a second control when a second start event set in advance occurs after the first control is executed, the second control causing the document sheet conveying device to sequentially select the first conveyance process or the third conveyance process for each of the document sheets based on the conveyance history information and execute the selected process.

2. The image reading apparatus according to claim 1, further comprising:

a thickness sensor configured to determine a thickness of each of the document sheets conveyed along the first incoming path, wherein

in the first control, the control portion selects which of the first conveyance process and the second conveyance process is to be executed by the document sheet conveying device based on a result of determination by the thickness sensor.

3. The image reading apparatus according to claim 1, further comprising a display device, wherein

the control portion causes the display device to display information at a point in time after the first control starts and before the second control starts, the information providing guidance on how one or more of the document sheets on the second tray are moved onto the first tray.
